UNITED STATES PATENT OFFICE.

JOHN H. KEYSER, OF NEW YORK, N. Y.

GAS HEATING AND COOKING STOVE.

SPECIFICATION forming part of Letters Patent No. 276,049, dated April 17, 1883.

Application filed January 6, 1883. (No model.)

To all whom it may concern:

Be it known that I, JOHN H. KEYSER, a citizen of the United States, residing in the city, county, and State of New York, have invented a new and useful Improvement in Gas Heating and Cooking Stoves, of which the following is a specification.

My invention relates to a gas-stove which is intended to confine all of the heat arising from the burning gas, and which compels it to spend all of its force by radiation, absorption, and a downward circulation in the same chamber in which it is first discharged from the gas-burner, the only provision for its escape being the open bottom of the chamber and the open bottom of the base upon which the chamber rests, and such an escape, if it occurs, being caused by a reverberation of the heat after it has passed to the closed top of the chamber and against the closed side wall of the same.

My invention consists—

First. In the combination, with the cylinder having a door extended down to its lower edge, and which is made without diving-flues, and which confines the whole heat from the gas-burner and reverberates it all upon articles being heated or cooked within the cylinder, of a gas-burner applied centrally of the cylinder, and entirely below said cylinder and its door, and provided with an induction-pipe, which is an extension of the head of the burner. By this combination the whole length and capacity of the chamber is utilized as a heat accumulating and reverberating chamber, and also as a chamber in which vessels or pans may be placed upon supports entirely above the gas-flame, but into which the said flame circulates.

Second. It consists in an adjustable air-admission thimble or ferrule at the outer end of the gas-burner induction-pipe, said ferrule being provided with an air-passage, and attached to the end of the gas-service pipe, and the same serving to admit such quantity of air, along with the gas, on the passage of the same to the burner, as the nature or quality of the gas flowing through the pipe may demand.

Third. It consists in the combination, with a base-support of a gas-stove provided with a cross-bar, of a gas-burner and head having an extension induction-pipe and a pivot screw-bolt and nut, whereby the burner can be sus-

pended below the cylinder of the stove, with its connected pipe at any convenient angle for connection with the gas-service pipe.

In the accompanying drawings, Figure 1 represents a vertical central section of my gas-stove; and Fig. 2, a detail top view of the thimble or ferrule for admitting and regulating the admission of air, along with the gas, to the burner.

A in Fig. 1 represents a cylinder or chamber closed at top and sides and open at its bottom, G. This cylinder is not intended to be provided with draft-flues or outlets at any point, and the only escape from it will be at its lower end. In this chamber a door, B, having mica in it, is provided, and this door will extend from near the top to the extreme lower edge of the cylinder, as shown.

A' represents a base-ring or other suitable support for the cylinder, and when the cylinder is placed upon this ring a circular ledge, a, will be formed by the support all around the inside of the cylindrical chamber, at a point above that where the gas-burner C terminates. Across the ledge a, below its top, a bar, d, is provided, and to this bar the gas-burner C, gas-burner head H, and gas-induction pipe H' are suspended by means of a pivot clamping-bolt, b, as shown. The burner C, head H, and pipe H' are cast together, and in the burner, which is cylindrical, fine reticulations or gage-wire outlets for escape of the gas while burning are provided. The induction-pipe passes from the head through the base-support A', as shown.

From an inspection of the drawings it will be seen that the gas-burner is entirely below the cylinder A, and that as the door B extends down to the bottom edge of the cylinder A vessels, pans, or other utensils can be placed through the door into the cylinder or chamber, close to the gas-burner flame, without resting upon the burner. If desired, a bar or grating can be placed upon the ledge a and these vessels set upon the bar or grating; but instead of this, the vessels may rest upon the cross-bar d, as found best. Thus it will be seen that the whole length and capacity of the cylinder is utilized as a heating or a cooking chamber. Besides this, all the highly-inflamed products of combustion pass up to the top of the cham-

ber and accumulate until by a reverberatory action they descend to the lower part of the cylinder, and if all their heat is not absorbed or radiated they will pass out under the lower edge of the cylinder. This construction of stove gives a powerful heat from a small consumption of gas, and it affords great capacity for cooking purposes, and at the same time answers as an illuminator through its mica door B, which answers as a means of access for lighting the burner, as well as for the purposes before mentioned.

To the gas-induction pipe H' of the burner an adjustable ferrule or thimble, D, is attached, and this thimble connects the said pipe with the service-pipe F, as shown. In the thimble or ferrule, on one side, a hole or air-passage, E, is provided for the admission of air into the induction-pipe H', along with the gas which is flowing from the service-pipe into said induction-pipe, and from thence into the burner-head. The shape of the outer end of the induction-pipe, as shown, is such that air has freedom to flow into said pipe when the hole in the ferrule or thimble is opened to a greater or less extent, but not otherwise. The object of this ferrule or thimble is to enable the user of the stove, by sliding it over the end of the pipe H', to so adjust the size of the air-passage that just the quantity of air required shall be admitted into the burner-head and to the burner, along with the gas, and by this means he is enabled to measure and regulate the amount of air necessary, according to the pressure or quality of the gas from the gasometer. This device forms an important improvement in the construction of gas-burners.

Another important improvement is the cross-bar d and the pivot-bolt applied below the cyl-

inder A, by which the burner is suspended, for with this contrivance the burner may be set with its induction-pipe at any convenient angle for connection with the gas-service pipe and then be readily clamped in position, while the bar will answer, also, for supporting cooking utensils.

What I claim as my invention, and desire to secure by Letters Patent, is—

1. The combination, with the cylinder A, which has a door, B, extended down to its lower edge, and which confines the heat from the gas-burner and reverberates the whole upon articles being heated or cooked within the chamber, of a gas-burner applied centrally of the cylinder, and entirely below said cylinder and door, and provided with an induction-pipe which is an extension of the head of the burner, substantially as and for the purpose described.

2. The adjustable thimble or ferrule D at the outer end of the induction-pipe of the burner, provided with an air-passage, E, and connected with the service-pipe F, whereby the proper proportionate amount of air to be admitted and mixed with the gas, in its passage to the burner, can be regulated, substantially as described.

3. The combination of the base-support A', provided with the cross-bar d, the cylinder A, applied above the base, the burner C, with its head H, and induction-pipe H', and the pivot clamping-bolt b, substantially as and for the purpose described.

JOHN H. KEYSER.
